US00D972948S

(12) **United States Design Patent** (10) Patent No.: **US D972,948 S**
Mostov et al. (45) Date of Patent: **** Dec. 20, 2022**

(54) **GLOBAL POSITIONING DEVICE FOR TRACKING CARGO**

(71) Applicant: **Obshchestvo s ogranicennoy otvetstvennost'yu "KIRSEN"**, Saint Petersburg (RU)

(72) Inventors: **Kirill Mostov**, Saint Petersburg (RU); **Valeriy Alexeev**, Moscow (RU)

(73) Assignee: **Kirsen Integrated Solutions and Systems LLC**, Sparks, NV (US)

(**) Term: **15 Years**

(21) Appl. No.: **35/511,948**

(22) Filed: **Apr. 15, 2020**

(80) **Hague Agreement Data**

Int. Filing Date: **Apr. 15, 2020**

Int. Reg. No.: **DM/214459**

Int. Reg. Date: **Apr. 15, 2020**

Int. Reg. Pub. Date: **Jun. 4, 2021**

(51) **LOC (13) Cl.** **10-04**

(52) **U.S. Cl.**

USPC **D10/70**

(58) **Field of Classification Search**

USPC D10/65, 70

See application file for complete search history.

(57) **CLAIM**

The ornamental design for a global positioning device for tracking cargo, as shown and described in the Embodiment on Figures 4.1-4.7.

DESCRIPTION

4. Global positioning device for tracking cargo

4.1 : Top

4.2 : Left

4.3 : Front

4.4 : Right

4.5 : Back

4.6 : Bottom

4.7 : Perspective
